DESIGN FOR A COAT

Sidney Dumler, New York, N. Y.

Application December 1, 1943, Serial No. 111,853

Term of patent 3½ years

To all whom it may concern:

Be it known that I, Sidney Dumler, a citizen of the United States of America, residing in New York, county of New York and State of New York, have invented a new, original, and ornamental Design for a Coat, of which the following is a specification, reference being had to the accompanying drawing, forming part thereof.

Fig. 1 is a front view of a coat showing my new design.

Fig. 2 is a rear view thereof.

I claim:

The ornamental design for a coat, substantially as shown.

SIDNEY DUMLER.
